Primary Examiner — Susan E Krakower*Assistant Examiner* — L. A. Grabenstetter(74) *Attorney, Agent, or Firm* — Westerman, Hattori, Daniels & Adrian, LLP(57) **CLAIM**

The ornamental design for a heat exchanger for an air conditioner, as shown and described.

DESCRIPTION

FIG. 1 is a front, right side, and top perspective view of a heat exchanger for an air conditioner showing our new design;

FIG. 2 is a front view thereof;

FIG. 3 is a right side view thereof;

FIG. 4 is a top plan view thereof;

FIG. 5 is a left side view thereof;

FIG. 6 is a rear view thereof; and,

FIG. 7 is a bottom plan view thereof.

The broken lines depict unclaimed portions of the heat exchanger for an air conditioner.
